(57) **CLAIM**

The ornamental design for a spice mill, as shown and described.

DESCRIPTION

Fig. 1.1 is a back elevational view of a spice mill showing my new design;

Fig. 1.2 is a bottom plan view thereof;

Fig. 1.3 is a front elevation view thereof;

Fig. 1.4 is a right side elevation plan view thereof;

Fig. 1.5 is a left elevation view thereof;

Fig. 1.6 is a top plan view thereof; and

Fig. 1.7 is an upper perspective view thereof.

The broken lines and the areas within them in Figure 1.2 depict portions of the spice mill that form no part of the claimed design.

The oblique shade lines in the drawings depict a surface that is transparent.
